UNITED STATES PATENT OFFICE.

LANCASTER Z. JENKINS, OF PHILADELPHIA, PENNSYLVANIA; ELIZABETH JENKINS, HOWARD H. BEEMAN, AND WILLIAM M. BOENNING, EXECUTORS OF SAID LANCASTER Z. JENKINS, DECEASED.

ATTACHMENT FOR BRIDLING BRUSHES.

No. 861,657.

Specification of Letters Patent.

Patented July 30, 1907.

Application filed August 1, 1906. Serial No. 328,702.

To all whom it may concern:

Be it known that I, LANCASTER Z. JENKINS, a citizen of the United States, residing in the city and county of Philadelphia, State of Pennsylvania, have invented a new and useful Attachment for Bridling Brushes, of which the following is a specification.

My invention consists of a device of novel construction for retaining the bridle of a brush in position, the same embodying a clip with which the bridle is engageable and a shank which is located within the ferrule and interlockingly held therein.

Figure 1 represents a perspective view of a brush and an attachment for the bridle thereof embodying my invention applied thereto. Fig. 2 represents a section 15 of a portion on line $x-x$ Fig. 1, the bridle having been removed. Fig. 3 represents a section of a portion at a right angle to Fig. 2. Fig. 4 represents a perspective view of the attachment removed from the brush. Fig. 5 represents a face view of a blank for forming a 20 differently-shaped attachment.

Similar letters of reference indicate corresponding parts in the figures.

Referring to the drawings: A designates a brush composed of the bristles B, the ferrule C, the handle D and 25 the bridle E, all of usual form.

F designates attachments for retaining the bridle in position, each of the same consisting of the shank G, the clips H and base J, said shank and clips rising from said base, said clips being bent outwardly from their 30 places of connection with said base, it being seen that the shank is of tapering form, it widening from the base to its upper end, said shank being fitted within the ferrule and lying against the inner wall of the same and being pressed against by the adjacent portions of the bristles within the ferrule.

The clips H are on the exterior of the ferrule, the bends K on their lower ends forming shoulders which abut against the bottom edge of the ferrule, whereby the attachment may be readily seated on the ferrule. 40 In this position of parts, the bristles are forcibly driven

into the ferrule, whereby they press the shanks against the ferrule and as said shanks are of tapering form as has been said, they dovetail with the adjacent bristles and interlock therewith, so that the attachments are prevented from being withdrawn at the open or bottom 45 end of the ferrule, it being evident that the ends of the bridle are connected with the clips H and thus it is reliably prevented from disconnection from the brush.

The bases J of the attachments are below the open or bottom end of the ferrule and have the adjacent portions of the bridle wound around the same and abut against the shoulders K which latter thus prevent any possible slipping of the bridle over the ferrule towards the handle end of the latter.

The portions of the bridle engaging the clips H may 55 be readily removed therefrom and re-applied and in the latter condition may be reeved around the clips so as to be prevented from slipping thereon.

In Fig. 5, I show a modification where the attachment is composed of the shank G', clips H' and base J', 60 slightly different from that of the other figures.

Having thus described my invention, what I claim as new and desire to secure by Letters Patent, is:

1. As an improved article of manufacture, a brush 65 bridle attachment comprising a dovetailed shank, clips out of the plane of said shank, a base from which said shank and clips extend, and shoulders formed at the junction of said clips and base, at the narrower end of said shank, the whole adapted for use with a ferrule with the shank upon the inner side of the ferrule and the clips upon the outer 70 side thereof and the base disposed beneath the bridle.

2. A brush having a ferrule and a bridle, combined with an attachment comprising a wedge shaped shank disposed within the ferrule, a base extended beneath the lower edge of the ferrule to extend within the bridle, and clips with 75 shoulders at their junction with the base, said shoulders engaging the ferrule upon their inner faces and the bridle upon their under faces, with the end of the bridle secured to said clips.

LANCASTER Z. JENKINS.
